TRACK SYSTEM FOR TOY ELECTRIC
RAILWAYSLemuel W. Short and Dean W. Short,
Beaverton, Oreg.

Application May 18, 1949, Serial No. 93,992

1 Claim. (Cl. 104—148)

1

This invention relates to improvements in miniature railroad systems and more especially to a track system and arrangement including a main endless track, such as a circle or oval, which is made up of interconnected two rail track sections, and a crossover track made up of interconnected two rail track sections, the crossover track being insulated from the main track and being supplied with electrical energy from a source independent of the source for the main track and being so arranged that the circuit in the crossover track is completed by the pick-up device on a car as the car travels over the crossover tracks. Thus, one of the primary objects of this invention is to provide insulated gaps between certain sections of the crossover track and other sections connected to the main track and to provide conducting wheels on a car, the gaps being bridged by the wheels and the spacing of the gaps being correlated with the longitudinal spacing and relationship of the conducting wheels so that uninterrupted travel of the car from the main track onto the crossover, over the crossover, and from the crossover back onto the main track is insured.

It is one of the principal objects of the invention to provide means for supplying continuous flow of electric energy, without interruption, to the said pick-up device of the car as it moves along the rails and enters the crossover insulated section of track before it completely leaves the insulated section of track adjacent to it.

A further object of the invention is the provision of means, when used with suitable switches and track layout, for completing a reverse loop to reverse the direction of travel of train or locomotive without interruption. Heretofore this has been considered impossible with a two rail system of the conventional type due to the fact that in making such a reverse loop the rails change relative positions with respect to each other and a short circuit of electrical conducting rails would result.

These and other objects will appear as our invention is more fully hereinafter described in the following specification, illustrated in the accompanying drawing and finally pointed out in the appended claim.

In the drawings:

Figure 1 is a top plan view of one arrangement of a miniature railroad track system embodying sections of track made in accordance with our invention.

Figure 2 is an enlarged side elevation of one of the sections of track shown in Figure 1 and show-

2

ing a miniature railroad car also made in accordance with our invention operatively mounted upon said track. This view is taken approximately along the line 2—2 in Figure 1.

5 proximately along the line 3—3 of Figure 2.

Figure 3 is a sectional top plan view taken approximately along the line 3—3 of Figure 2.

Referring now more particularly to the drawings:

10 In Figure 1 reference numeral 1 indicates generally an endless track which may be laid in a wide variety of arrangements such as in figure 8's, circles, and in various other patterns as employed in miniature railroad systems. In the particular arrangement shown in Figure 1 the track 1, which for convenience will hereinafter be referred to as the main track, comprises a plurality of straight and curved sections 2 and 3, respectively, consisting of two rails 4 and 5 held apart in spaced relation to each other by ties 6 and connected with each other as at 7 all in the conventional manner. The straightaway and curved portions of the main track are connected with switches 8 to which the ends of a crossover track generally indicated at 9 are also connected.

15 Each of the sections 2 and each of the sections 3 of the main track are electrically connected with each other through the usual telescopic fittings at their ends in the usual manner so that 20 electric current passing through the tracks may be picked up by the miniature car operating on the tracks. Electric current is supplied to the outside rail 4 of the main track by one lead 19 coming from a transformer 11 supplied with current through wires 12 from any convenient source of supply. The other lead 13 of the transformer connects with the inside rail 5.

25 The crossover track 9 is made up of certain sections, for example, those indicated at 14, 15 and 16 which are identical with the straight away sections 2 of the main track. Other sections of the crossover track which constitute one of the important features of my invention are indicated at 17 and 18. The crossover track is supplied with 30 electric current by lead wires 19 and 20 coming from a transformer 21 of the type indicated at 11.

35 These sections of the crossover track indicated at 17 and 18 are identical with each other and as best illustrated in Figures 2 and 3 each comprises two rails 22 and 23 and each rail is made of two aligned sections 24—25 and 26—27 respectively. The ends of the aligned sections of rails 24 and 25 and 26 and 27 are axially spaced from each other by insulated gaps 28 and 29, the gaps being 40 maintained by small blocks of insulating mate-

3

rial suitably positioned within the gaps. In connection with the said aligned sections 24—25 and 26—27, attention is directed to Fig. 3 wherein it will be noted that the aligned sections 24 and 25 are of unequal length, the section 24 being the longer and that the aligned sections 26—27 are likewise of unequal length, the section 27 being the longer. The long sections 24 and 27 are diagonally opposed as are the short sections 25 and 26. Thus, the gaps 28 and 29 between the sections 24—25 and 26—27, respectively, are diagonally opposed and longitudinally spaced. In other words, the gaps are spaced longitudinally apart and are on opposite sides of the sections 17 and 18 of the crossover track. This can be seen in Fig. 1. All of the rail sections are secured to ties 38 in the usual manner and are insulated therefrom by the conventional insulating material 30A.

The miniature railroad car we have illustrated in Figure 2 may be a tender or any other type of car having front and rear trucks generally indicated at 31 and 32, respectively. Each truck is of conventional design comprising side plates 33 and 34 depending from a circular plate 34A by means of which the truck is pivotally connected to the underside of the car in the usual manner. Extending across and secured to the plates 33 and 34 are two axles 35 and 36 upon which are rotatably mounted two pairs of wheels 37 and 38. The axles 35 and 36, the side walls 33—34 and the pair of wheels 37 are made of metal and thereby provide an electrical conductor across the gap 28 (see front truck) as the truck passes thereover. The opposite wheels 38 of said truck are of course made of any approved type of insulating material such as "Bakelite," fibre, hard rubber or the like. In the rear truck 32 the arrangement of the metallic and insulating wheels is reversed, that is to say, the pair of wheels 40 are of insulating material and the opposite pair 41 are made of metal as are also the axles 42, side plates 43 and 44.

As shown in Fig. 3, the conducting wheels 37 bridge the gap 28 simultaneous with the bridging of the gap 29 by the conducting wheels 41. The circuit is completed from the track sections 24—25, the wheels 37, through the pick-up device of the car to the wheels 41 and track sections 26—27. The longitudinal spacing of the wheels 37 and the wheels 41 matches the longitudinal spacing of the gaps 28 and 29 and, obviously, the conducting wheels 37 and 41 are diagonally opposed in the same fashion as the gaps 28 and 29. Therefore, considering Fig. 1, it can be understood that the car will be energized by the source 11 as it moves on the track section 16 of the crossover and as the wheels 37 bridge the gap 28, the wheels 41 will simultaneously bridge the gap 29. Until such time, the car is powered by the source 11, but when the gaps are bridged, the car's pick-up device is energized by the source 21. An uninterrupted movement of the car is thereby obtained.

Reverting to Figure 1, it will be seen that, due to the insulated gaps 28 and 29 in either sections of the track 17 and 18, the crossover track may be electrified and at the same time insulated from electrical contact with the main track due to the open circuit caused by the gaps 28—29 but which are bridged only as the trucks of the car pass over the gaps to close the circuits thereacross. One end of each track of the crossover track is mechanically connected to its respective switch base 3 of insulating material and also through a pointed block of insulating material indicated at 45, but electrically connected with the outside and

4

inside rails of the main track by means of conductors 4A and 5A respectively. By this arrangement, current flows into both ends of the crossover track 9 up to the insulated points 28 and 29 where the intermediate sections of the crossover track are supplied with a separate current from the transformer 21. As the trucks 31 and 32 of the car pass over the gaps 28 and 29, they close the circuit across the gaps and thus pick up energy from the source 21 through wires 19—20 as the trucks roll away from the sections energized from source 11 through wires 10 and 13.

The axles of each truck are also interconnected by a brush indicated at 46 and 47 to which wires 48 and 49, are connected, respectively, and which extend outwardly through one end of the car for electrical connection with a motor equipped locomotive or other towing car.

While we have shown a particular form of embodiment of our invention, we are aware that many minor changes therein will readily suggest themselves to others skilled in the art without departing from the spirit and scope of the invention. Having thus described our invention, what we claim as new and desire to protect by Letters Patent is:

A miniature railroad track system comprising in combination, an endless main track made up of a plurality of two-rail track sections interconnected at their ends, a crossover track positioned inside the endless main track and comprising a plurality of two-rail track sections interconnected together, said crossover track including end track sections, switches connecting said end track sections of the crossover track to opposite points of the main track, said switches having two-rail sections connected to the end track sections and each of said two-rail sections having a rail adjacent the inner rail of the main track and said rail of each of said sections being insulated from the inner rail of the main track, the end track sections of the crossover track being electrically connected to the main track, said crossover track having track sections intermediate said end track sections thereof, each of certain of said intermediate track sections having two aligned rails of unequal length on one side spaced longitudinally from each other at their adjoining ends to form an insulating gap at one end of said section and two aligned rails of unequal length on the other side spaced longitudinally from each other at their adjoining ends to form an insulating gap at the other end of said section, said insulating gaps being thereby longitudinally spaced and diagonally opposed, a first source of electrical energy connected to the main track and to the end track sections of the crossover track and supplying electrical current to the track sections of the main track and to the end track sections of the crossover track, a second source of electrical energy connected to the rails of the intermediate track sections of the crossover track, and a railroad car mounted upon longitudinally spaced front and rear trucks operable on said tracks and one truck having conducting wheels on one side thereof and electrically interconnected with each other and having insulating wheels on the opposite side of the truck, and the other truck being structurally identical with the first mentioned truck but arranged in a reverse position on the track wherein its insulated wheels are located on the rail opposite to the rail on which the insulated wheels of the first mentioned truck are located and its conducting wheels are located on the rail opposite to the rail on which the conducting

wheels of the first mentioned truck are located, will close an electrical circuit at one end of each of said certain of said intermediate track sections with the conducting wheels on one truck and at the opposite end of said certain of said intermediate track sections with the conducting wheels on the truck at the opposite end of said car, said conducting wheels of the one truck being longitudinally spaced from the conducting wheels of the other truck the same distance as the longitudinal spacing of the gaps to thereby bridge the gaps. 10
